UNITED STATES PATENT OFFICE.

HARRY LIEBECK, OF PHILADELPHIA, PENNSYLVANIA, ASSIGNOR TO SCOTT PAPER COMPANY, A CORPORATION OF PENNSYLVANIA.

MACHINE FOR MAKING TOILET-PAPER ROLLS.

1,081,507.

Specification of Letters Patent.

Patented Dec. 16, 1913.

Application filed August 5, 1908. Serial No. 447,007.

To all whom it may concern:

Be it known that I, HARRY LIEBECK, a citizen of the United States, and a resident of the city and county of Philadelphia, State 5 of Pennsylvania, have invented an Improvement in Machines for Making Toilet-Paper Rolls, of which the following is a specification.

My invention has reference to machines 10 for making toilet paper rolls, and consists of certain improvements which are fully set forth in the following specification and shown in the accompanying drawings which form a part thereof.

15 The object of my invention is to provide a construction of paper winding machine for making toilet paper packages in roll form which will permit of a practically continuous operation by bringing into winding 20 position one mandrel after another in rapid succession, with the result that the output of a single machine is greatly increased over what has heretofore been possible with this class of machine.

25 My invention consists in the combination of means for perforating, (with or without slitting a web of paper) with rewinding means comprising an adjustable frame provided with two or more detachable mandrels arranged to be successively brought 30 into operative winding position, and means for rotating the mandrels when in operative winding position; further, in a machine of the character stated, when provided with 35 means for insuring the rotation of the mandrels only when in winding position, whereby the operator may withdraw a filled mandrel when out of winding position and after removing the paper rolls readjust the mandrel upon the carriage and into operative 40 relation with the means for rotating it; further, in providing the above described machine with perforating cutters which so co-operate with the slitting cutters that the adjacent webs, formed by the slitting cutters 45 upon the single wide web, shall be perforated or cut, whereby the incisions shall be out of transverse alignment and the weakest portions of the perforated webs will not all 50 be subjected to the winding tension at one time.

My invention also comprehends details of construction which, together with the features above specified, will be better understood by reference to the drawings, in which:

Figure 1 is a side elevation of a paper rewinding machine embodying my invention; Fig. 2 is a plan view of the same with a portion broken away; Fig. 3 is a sectional elevation of the same on line $x-x$ of Fig. 2; 60 and Figs. 4 and 5 are sectional views of the means for rotating the mandrels.

2 is the main frame of the machine.

3 is the supporting shaft or mandrel upon which the large roll of paper is placed; and 65 said shaft 3 is provided with a brake wheel 4 against which a friction shoe 5 may be pressed under control of the screw shaft 6 extending to the front of the machine, whereby a frictional resistance may be put 70 upon the large paper roll to maintain the paper web 7 under tension during the slitting, perforating and rewinding operations. Any other suitable means may be employed 75 for providing this tension to the paper web.

The web of paper 7 passes under a guide and feed roller 8, then upward and over a drum 9 and thence to the winding mandrel 35. While the paper is passing about the drum 9 it is first perforated transversely at 80 intervals by the perforating blades 16 of a roller 10 and then slit longitudinally by the slitting cutters 12 on the shaft 17. The drum 9 is made with a series of circumferential cutting edges 15 for co-operating with the slitting cutters 12, and is also provided with a series of transverse grooves 14 for co-operating with the perforating cutting blades 16 for partly severing the web 7. By the combined action of the cutters 12 85 and blades 16, a series of narrow webs of paper are formed, each of which is perforated transversely at intervals, so as to form short connected sheets which are simultaneously wound upon the mandrel 35. 90

To prevent the pull of the mandrel rupturing the perforated webs, I prefer to arrange the blades 16 and the grooves 14 in such manner that the adjacent transverse perforations, before slitting takes place, shall be cut out of alignment or staggered, as will be understood by reference to Fig. 2. By this means there is considerable body of paper between the adjacent transverse perforations, and the frictional contact of such paper with the drum feeds it forward 100 and supports it during the slitting operation. The feeding action of the roller 8 (which may be covered with rubber) removes all excessive strain from the webs during the 110

winding operation of the mandrel 35. The mandrel 35 is driven by frictional drive means so that the web is wound under uniform tension.

5 The drum 9, slitting cutters 12, perforating roller 10 and feeding roller 8 are all geared together by gearing 18 to insure their speeds being such as to properly co-operate in the manner above described. The

10 drum 9 is driven by a band wheel 19 having a disengaging clutch 52 of any suitable construction, which may be put into or out of action by a shifter shaft 20 having a pin

15 24 coöperating with a fixed cam surface 25, said shaft 20 being rocked by crank 21, link 22 and hand lever mechanism 23. Any

other suitable means may be employed for putting the machine into and out of operation. A hand wheel 19^a may be employed

20 on the shaft of the drum 9 for adjusting the machine when the clutch 52 is out of gear.

The general construction of the machine above described may be modified as to its elements and arranged to produce one or 25 more webs to be rolled at one time, but where there are a plurality of narrow webs to be made and wound, I consider it most important to arrange the perforating blades 16 out of alinement.

30 I will now refer more particularly to the means for and manner of winding the perforated strips of paper upon a mandrel to form the rolls of paper in commercial form.

26 35 is a pivoted frame which is pivoted at 27 to the main frame 2, and has, at its upper or free end, a transverse shaft 29 journaled therein and provided with disks 30 near each end. Between the disks 30 and removably supported, are the mandrels 35

40 upon which the webs of paper are wound. One of the disks 30 is provided with a series of shafts 36 having pinions 49 on one end and chucks 37 on the other end with

45 which the end of the mandrel 35 engages and by which it is rotated. The mandrel 35 is provided with a pin 38, as shown in Fig. 4; and this pin engages a shoulder in the chuck 37 so that the rotation of the latter causes the mandrel to be rotated with

50 it. The other end of the mandrel 35 is detachably supported upon a spring actuated center pin 40, which is carried in the other disk 30 and spring pressed toward the mandrel by means of a coil spring 41, as shown

55 in Fig. 5. I have shown four of the chucks 37 on one of the disks 30 and four of the spring actuated center pins 40 on the other disk 30, so that there is capacity for employing a plurality of mandrels between the

60 two disks 30 at one time. One of the disks is provided with a series of notches 31 corresponding in number to the spring actuated center pins 40 and engaging these notches is a locking pin 33 carried by a

and held in locking position by means of a spring 34. By reference to Fig. 3, it will be seen that, by disengaging the pin 33 from the notch 31 the shaft 29, together with its disk 30 and mandrels, may be rotated so as to bring into operative position another mandrel to take the place of the one upon which the paper webs have been fully wound.

70 The operation of unlocking the shaft 29 and its disks and rotating it to bring a new mandrel into operative position may be accomplished without interrupting the operation of the machine as a whole except for a moment; and because of the facility of removing a filled mandrel and bringing a fresh mandrel into operative position, the capacity of the machine is greatly increased. When the machine is in normal operation, the pivoted frame 26 leans toward the drum 85 9 as in Fig. 1; and when the mandrel is filled, the frame assumes a vertical position as shown in Fig. 3, at which time it becomes locked by means of the notch and locking lever 28. By raising this lever 28, 90 the frame, together with its shaft 29, may be thrown outward and away from the drum 9 for permitting access thereto.

95 The rotation of the mandrel 35 is accomplished in the following manner. A chain wheel upon the drum 9 drives a chain pulley 44 upon the shaft 27 by means of a chain or belt 43. The pulley operates a second pulley 45 through a friction clutch 50, the friction thereof being produced by means 100 of the spring 51 which presses the flanged part of the pulley 44 toward the flanged part of the pulley 45. The pulley 45 drives a pulley 47 by means of a chain or belt 46, the said pulley 47 being secured upon a 105 shaft journaled in the pivoted frame 26 and provided with a gear 48. When the shaft 29 and its disks 30 are rotated into successive positions of adjustment and locked in said positions successively by the locking 110 means 32 and 33, the pinions 49 of the several chucks are successively brought into engagement with the rotating gear 48 which is journaled on the pivoted frame 26 carrying the shaft 29. In this way the chucks 115 are successively brought into operative position and rotated, for imparting rotation to their respective winding mandrels. From Fig. 1, it will be seen that the chuck nearest to the drum 9 will be rotated by means 120 of this power transmitting mechanism and consequently the mandrel connected with the said chuck will be caused to rotate. During the rotation of the mandrel, its speed will be governed by the amount of 125 paper to be wound which may pass to it from the drum 9, and a variation of this speed is permitted because of the presence of the friction clutch 50 between the two chain or belt wheels 44 and 45.

When the machine is in operation, the paper is attached to the mandrel with a small amount of paste; and the paper being wound upon the mandrel is allowed to continually rest against the surface of the drum 9, as indicated in Fig. 1, the said action being permitted by lifting the lever 28 and moving the frame 26 and its shaft 29 toward the said drum. As the webs of paper are rolled upon the mandrel and increase in diameter, they push the mandrel gradually away from the drum; and when the proper size of roll is completed, the frame 26 will have been moved from the position indicated in Fig. 1 to almost the position indicated in Fig. 3. The operator then pulls the frame 26 into engagement with the lever 28 which locks to the transverse rod 53 on the said frame and holds the same stationary. He may then stop the machine by throwing the stop lever mechanism 23. Previous to the stopping of the machine he has inserted an additional mandrel between the next chuck and center pin to come into operative position. When the parts have assumed the position indicated in Fig. 3 and the machine is stopped, the operator disengages the pin 33 from the notch 31 and rotates the shaft 29 with its disks and mandrels until the pin engages the next notch 31. The filled mandrel is then removed by disengaging it from the chuck and center pin and the paper webs broken and the ends thus made quickly attached to the new mandrel and, after disengaging the lever 28, the frame 26 with its shaft 29 is thrown into the position indicated in Fig. 1 and the lever device 23 again thrown to put the machine into operation. These operations are repeated with the introduction of every new mandrel.

It will be noted that when the disks 30 are rotated, the pinions 49 and the chuck carrying the next mandrel to be filled will be brought into engagement with the driving gear 48, and the corresponding gear 49 of the chuck which carried the mandrel which has just been filled is moved out of engagement with the said gear 48. It will also be seen that the mandrel is only rotated when in winding position and when the machine is in operation, so that it is evident that a new mandrel may be placed in position and a filled mandrel may be removed while the machine is in operation, because the chucks carrying the last mentioned mandrels are not being rotated.

I have shown my invention adapted to the slitting of wide web 7 into a series of narrower webs, all of which are simultaneously wound upon the same mandrel 35, but I do not restrict myself to such slitting, as the rewinding features of my invention may be applied to cases where only a single web is operated upon.

It is evident that the contact of the mandrel and paper thereon with the drum 9 may be employed to rotate them, but when the rewinding is to be done under sufficient tension to make a tight and solid roll, the positive rotating devices for the mandrel are necessary and in practice I prefer their use.

I have shown a form of chuck and center pin for holding the mandrel 37 in position which I have found excellent in practice, but it is evident that the mandrels may be removably held in place in any other suitable manner.

The important feature of my invention is the capacity of adjustment of the mandrels to the machine during its operation so that very little loss of time occurs in removing a filled mandrel and introducing another mandrel into operative position and connection with the paper webs; and the means for accomplishing this may be varied from that shown without departing from the spirit of the invention.

Having now described my invention, what I claim as new and desire to secure by Letters Patent, is:

1. In a machine for winding toilet paper into rolls, the combination of means for producing a series of transverse cuts across the paper web and repeated at intervals in the length of the web and in which the adjacent cuts of each series are out of alignment, and means for slitting the paper web longitudinally on lines intermediate of the transverse cuts of each series.

2. In a machine for winding toilet paper into rolls, the combination of means for producing a series of transverse cuts across the paper web and repeated at intervals in the length of the web and in which the adjacent cuts of each series are out of alignment, means for slitting the paper web longitudinally on lines intermediate of the transverse cuts of each series, and means for winding the series of narrow perforated webs of paper so formed into rolls.

3. In a machine for winding toilet paper into rolls, the combination of means for producing a series of transverse cuts across the paper web and repeated at intervals in the length of the web in which the adjacent cuts of each series are out of alignment, means for slitting the paper web longitudinally on lines intermediate of the transverse cuts of each series, and means for winding the series of narrow perforated webs of paper so formed into rolls consisting of an adjustable supporting frame movable to and from the perforating and slitting means, a detachable mandrel carried thereby upon which the paper webs are wound, and means for rotating the mandrel.

4. In a machine for making toilet paper into rolls, the combination of means for per-

- forating a web of paper transversely of its length to form connected sheets, with roll making devices consisting of a mandrel upon which the paper web is wound, a support 5 for the mandrel permitting it to move away from the means for perforating the web, and means on the support for moving the mandrel out of operative position and shifting another mandrel into position.
- 10 5. In a machine for making toilet paper into rolls, the combination of means for perforating a web of paper transversely of its length to form connected sheets, with roll making devices consisting of a mandrel upon 15 which the paper web is wound, a support for the mandrel permitting it to move away from the means for perforating the web, means on the support for moving the mandrel out of operative position and shifting 20 another mandrel into position, and locking devices for locking the last mentioned means on the support during the winding operation of the machine.
6. In a machine for making toilet paper into rolls, the combination of means for perforating a web of paper transversely of its length to form connected sheets, with roll making devices consisting of a mandrel upon which the paper web is wound, a support for 30 the mandrel permitting it to move away from the means for perforating the web, means on the support for moving the mandrel out of operative position and shifting another mandrel into position, and means 35 for positively rotating the mandrel when in operative position for winding the paper web.
7. In a machine for making toilet paper into rolls, the combination of means for perforating a web of paper transversely of its length to form connected sheets, with roll making devices consisting of a mandrel upon which the paper web is wound, a support for the mandrel permitting it to move away 40 from the means for perforating the web, means on the support for moving the mandrel out of operative position and shifting another mandrel into position, frictionally driven means having a rotating part carried 45 by the support, and a plurality of mandrel rotating chucks respectively engaging the rotating part of the frictionally driven means when holding the mandrel in operative winding position.
- 50 8. In a machine for making toilet paper into rolls, the combination of means for perforating a web of paper transversely of its length to form connected sheets, with roll making devices consisting of a mandrel upon 55 which the paper web is wound, a support for the mandrel permitting it to move away from the means for perforating the web, means on the support for moving the mandrel out of operative position and shifting 60 another mandrel into position, and means to 65 lock the support against movement after the roll of paper upon the mandrel has reached a predetermined size.
9. In a machine of the character described, means for guiding a web of connected sheets, combined with means for winding the web into rolls, consisting of a supporting frame movable to and from the guiding means for the web during the winding of the roll, an adjustable frame carried by the supporting frame and provided with a plurality of mandrel sustaining devices whereby different mandrels may be successively brought into winding position, and detachable mandrels for said mandrel sustaining devices. 7
10. In a machine of the character described, means for guiding a web of connected sheets, combined with means for winding the web into rolls consisting of a supporting frame movable to and from the 8 guiding means for the web during the winding of the roll, an adjustable frame carried by the supporting frame and provided with a plurality of mandrel sustaining devices whereby different mandrels may be successively brought into winding position, means for rotating the mandrel, sustaining device supporting the mandrel which is in winding position, and detachable mandrels for said 9 mandrel sustaining devices. 9
11. In a machine of the character described, means for guiding a web of connected sheets, combined with means for winding the web into rolls consisting of a supporting frame movable to and from the 10 guiding means for the web during the winding of the roll, an adjustable frame carried by the supporting frame and provided with a plurality of mandrel sustaining devices whereby different mandrels may be successively brought into winding position, means for rotating the mandrel sustaining device supporting the mandrel which is in winding position, locking means for holding 11 adjustable frame against being moved on the supporting frame during the winding operation, and detachable mandrels for said mandrel sustaining devices. 11
12. In a machine of the character described, the means for forming a web of 11 paper composed of a series of connected sheets, combined with means for winding said web into rolls consisting of a pivoted frame, a rotatable frame journaled in the free end of the pivoted frame, a plurality 12 of mandrel chucks on the rotatable frame arranged at a distance apart and substantially equidistant about its pivotal axis, detachable mandrels for said chucks, means for rotating said chucks when in operative 12 winding position, and means to lock the rotatable frame in a plurality of positions so as to hold the several chucks one at a time in operative winding position.
13. In a machine of the character de- 13

scribed, the means for forming a web of paper composed of a series of connected sheets, combined with means for winding said web into rolls consisting of a pivoted frame, a rotatable frame journaled in the free end of the pivoted frame, a plurality of mandrel chucks on the rotatable frame arranged at a distance apart and substantially equidistant about its pivotal axis, detachable mandrels for said chucks, frictionally driven means for rotating said chucks when in operative winding position, and means to lock the rotatable frame in a plurality of positions so as to hold the several chucks one at a time in operative winding position.

14. In a machine of the class described, means for forming a web of paper composed of a series of connected sheets, combined with means for bringing a plurality of winding mandrels successively into operative position for winding the web into rolls and causing the mandrel to be moved away from the means for forming the web of paper during the winding operation, and driving means for rotating the mandrels when brought into operative winding position, whereby a filled mandrel and paper roll may be removed and a new mandrel inserted into the machine during the winding operation of another mandrel.

15. In a machine for making toilet paper into rolls, the combination of suitable perforating mechanism, a rotatable frame provided with a plurality of detachable mandrels, and means for moving the rotatable frame bodily to and from the perforating mechanism, whereby different mandrels may be brought into winding position successively.

16. In a machine for making toilet paper into rolls, suitable mechanism for dividing

a web of paper into a series of narrower webs each perforated at intervals in its length, combined with a rotatable frame provided with a plurality of detachable mandrels each having a length substantially equal to the sum of the width of the narrow webs and for simultaneously winding said plurality of narrow webs into separate rolls while they are still in connection with the wide web, means for bringing the plurality of detachable mandrels into winding position successively, and means common to the several mandrels for rotating them when brought into winding position.

17. In a machine for making toilet paper into rolls, suitable mechanism for dividing a web of paper into a series of narrower webs each perforated at intervals in its length, combined with a rotatable frame provided with a plurality of detachable mandrels each having a length substantially equal to the sum of the width of the narrow webs and for simultaneously winding said plurality of narrow webs into separate rolls while they are still in connection with the wide web, means for bringing the plurality of detachable mandrels into winding position successively, means common to the several mandrels for rotating them when brought into winding position, and means for moving the rotatable frame carrying the detachable mandrels to or from means for dividing and perforating the web of paper.

In testimony of which invention, I have hereunto set my hand.

HARRY LIEBECK.
